UNITED STATES PATENT OFFICE.

WILLIAM A. McELNEY, OF WESTFIELD, MASSACHUSETTS.

ADVERTISING DEVICE.

Application filed July 25, 1925. Serial No. 45,988.

My invention relates to improvements in advertising devices in the form of shields, caps, or mouth-pieces applicable to the small ends of cigars, and consists essentially of a 5 hollow member of the general shape and size of the tapered or pointed-end portion of a cigar, being open at the large end to receive the cigar butt, and perforated at the small end for the passage of the smoke 10 therefrom, and provided intermediate of its ends with exterior projections in the shape and form of letters, numerals, or other characters or figures, that disseminate information and partake of the nature of an 15 advertisement, all as hereinafter set forth.

This device may be made of very thin sheet-metal, such as aluminum, or of celluloid, gelatin, and other suitable thin material. Usually, in producing the device, a 20 piece of the particular sheet material used is first stamped out to produce a disc of the proper size, having an opening in the center thereof, and projections in the form of letters, numerals, or other characters or figures, struck up therein or therefrom and then this disc is transformed into a hollow member of the required shape and size, by 25 means of a punch and die. Male and female punch and die members are employed 30 for forming the indentations in one side and producing the elevations on the other side of the disc, except in the case of celluloid, and possibly that of gelatin, when only a female member is required.

The primary object of my invention is to 35 produce a device bearing integral, raised advertising matter, and adapted to fit on and serve as a mouth-piece for a cigar. This device is especially well adapted as a medium for the display of the trade-mark for 40 the cigar on which it is used and thereby removes the need for stamping the trade-mark on the cigar, or applying to the latter a band on which is printed the trade-mark. 45 The name of the manufacturer and the place of manufacture of the cigar, and other data or information may also be disseminated by means of this device. The device interferes 50 in no way with the drawing qualities of the cigar to which it is applied, but, if anything, improves such qualities.

It is necessary that a mouth-piece for a 55 cigar have a more or less broken, roughened, or uneven exterior surface in order that the same may be grasped securely between the lips and held in place, and the treatment of

my device to produce raised letters or characters on the exterior surface thereof furnish inherently the required broken surface or unevenness.

The punched or embossed parts of the device, being hollow inside, have edge portions which are in contact with the cigar and assist in retaining the device in place on the same.

Other objects and advantages will appear in the course of the following description.

I attain the objects and secure the advantages of my invention by the means illustrated in the accompanying drawings, in 70 which—

Figure 1 is a top plan of a blank after the same has been struck out and punched in readiness to be formed into a device which embodies a practical form of my invention; 75 Fig. 2, a side elevation of a device formed from said blank; Fig. 3, a central, longitudinal section through said device; Fig. 4, a side elevation of the device in place on a cigar, and Fig. 5, a top plan of a blank having the advertising matter arranged therein and thereon in circular formation, instead of in radial formation as in the first example.

All of the views, except Fig. 4, are on a 85 greatly enlarged scale.

Similar reference characters designate similar parts throughout the several views.

In Fig. 4, a cigar is represented at 1, and on the pointed or small end of said cigar is 90 an advertising device or mouth-piece 2 which will first be described.

The mouth-piece 2 is made from thin sheet material formed up from a blank or disc 3 which is stamped out, perforated in the center to provide an opening in the apex of said mouth-piece, as 4, through which the smoke is drawn from the cigar 1 when lighted, and embossed to produce projections on the exterior and indentations on the interior of the 100 mouth-piece, such projections having the form of letters and figures, the former being indicative of the name of a company and giving the name of the city wherein said company is located, and the latter being the 105 trade-mark in duplicate of said company. The company is assumed to be the manufacturer of the cigar.

In the present example the company is 110 designated by the letters "XYCO", the place as "ERIE", and the trade-mark as "71". Obviously any other letters or figures or

combinations of the same might be substituted for those herein appearing.

The company designation and the name of the place are embossed on one diameter of

- 5 the disc 3, respectively on opposite sides of the center or opening 4 therein, and the trade-mark appears twice on a diameter of said disc which is at right-angles to said first-named diameter, with one trade-mark
- 10 on each side of said center or opening. The letters and figures are arranged to read toward the apex of the mouth-piece 2, although such arrangement is not important, since they might be arranged to read in the
- 15 opposite direction, or some arranged to read in one direction, and some in the other.

The embossing may be done at the time the disc 3 is cut from the sheet and the opening 4 is punched therein, and then said disc 20 thus prepared is formed into the required shape with a suitable punch and die.

The mouth-piece 2 fits snugly onto the butt of the cigar 1, and the edges of the indentations produced by the embossing engage contiguous parts of the cigar and assist 25 in holding said mouth-piece in place thereon. The projections produced by the embossing afford a broken or uneven surface for the lips to grasp, and thereby enable 30 the mouth-piece with the cigar to be held by the lips without slipping, previous to and while the cigar is being smoked. Thus it is seen that the advertising characters inherently afford means for holding the device 35 in place on the cigar and between the lips, and so practically insure the retention of the trade-mark or other matter of information on the cigar until the latter is consumed, since the device will not easily slip off, and,

40 being serviceable as a sanitary mouth-piece which can be held safely and comfortably between the lips, is not liable to be pulled off and thrown away, which are very valuable considerations. In Fig. 3, the indentations are indicated by the numeral 5, and in Figs. 2, 3, and 4, the projections are indicated by the numeral 6.

Incidentally it may be observed that the small end of the cigar 1 must be left open 50 at its extremity, instead of being closed as in the case of an ordinary cigar unprovided with a mouth-piece, in order that the draft through the cigar will be uninterrupted or free when the smoker draws in his breath through the opening 4, and that portion of the cigar which is enclosed by the mouth-piece may be left in a more or less rough or unfinished condition because it is so enclosed

or covered. For sanitary reasons the mouth-piece 2 should be of sufficient length to prevent the teeth and lips from coming into direct contact with the tobacco.

Preferably the large end of the mouth-piece 2 is flared a little, as represented at 7, for the purpose of avoiding any liability of 65 tearing the wrapper of the cigar 1 when said mouth-piece is placed thereon.

Instead of embossing the disc 3 in a manner to arrange the advertising matter thereon radially, such disc may be embossed in a 70 manner to arrange the advertising matter thereon in a circle, as illustrated in Fig. 5, and it might be possible so to emboss the disc that the advertising matter would be arranged in some manner other than radially 75 or in a circle. Only the repeated trade-mark is represented in Fig. 5, but the company designation and the name of the place of manufacture, or other matter, might be interspersed with a less number of the trade- 80 marks. Naturally no limitation can be placed on the advertising matter to be embossed on the disc, beyond the limitations as to size and quantity or amount.

A cigar equipped with one of my advertising 85 devices is smoked in practically the same manner as a cigar which is not so equipped. After the cigar has been smoked the device is thrown away. Necessarily, therefore, the device must be produced at a 90 very small cost.

In addition to the changes and modifications hereinbefore pointed out, others may be made, especially in matters of material, size, and shape, without departing from the 95 spirit of my invention, or exceeding the scope of what is claimed.

What I claim as my invention, and desire to secure by Letters Patent, is—

1. As an improved article of manufacture, 100 an advertising device applicable to the tip end of a cigar, and comprising a hollow cylindrical seamless member conical at one end and having, intermediate of its ends, raised parts which serve the double purpose of 105 delineating matter of an informative character, affording gripping means to be grasped by the lips to prevent said device from slipping from between them.

2. The method of making an advertising 110 device consisting in embossing a disc, between the center and rim thereof, with information-disseminating matter, and in forming said disc into a hollow cylindrical member with a conical end.

WILLIAM A. McELNEY.
